ARMATURE WINDING MACHINE

Edward W. Collins, Anderson, Ind., assignor to
General Motors Corporation, Detroit, Mich., a
corporation of Delaware

Application April 10, 1948, Serial No. 20,325

5 Claims. (Cl. 242—13)

1

This invention relates to machines for winding armatures.

An object of the invention is to provide a machine which will thread wires into the slots of an armature core simultaneously. In the disclosed embodiment of the invention this object is accomplished by the use of a stationary wire placing device into which there pass a plurality of wires from a plurality of reels and a carriage or shuttle which supports two armature cores whereby the winding of one armature core can take place while the core that has been wound can be removed and replaced by an empty core onto which wires from the wound armature are passed and thereby anchored on the fresh core before the end leads of the wound armature coils are severed.

Further objects and advantages of the present invention will be apparent from the following description, reference being had to the accompanying drawings wherein a preferred embodiment of the present invention is clearly shown.

In the drawings:

Figs. 1 and 2 together form a side elevation of the machine.

Fig. 3 is a view in the direction of arrow 3 of Fig. 1.

Fig. 4 is a fragmentary sectional view on line 4—4 of Fig. 3.

Figs. 5 and 6 are plan and side views respectively of a wire anchoring device which is placed on the shaft of an armature which is the first of a series to be wound by the machine.

Fig. 7 is a view in the direction of arrow 7 of Fig. 8.

Fig. 8 is a sectional view on line 8—8 of Fig. 1.

Fig. 9 is a sectional view on line 9—9 of Fig. 1.

Fig. 10 is a sectional view on line 10—10 of Fig. 11.

Fig. 11 is a view of the stationary wire placing device looking in the direction of arrow 11 of Fig. 1.

Fig. 12 is a view in the direction of arrows 12 of Figs. 2 and 10.

Fig. 13 is a view on line 13—13 of Fig. 10, a portion of the wire placer having been removed.

Figs. 14, 15 and 16 are perspective views showing the operation of the machine.

Figs. 17 and 19 together form a side elevation of the spool rack with spools thereon and a diaphragmatic representation of the wires which pass from the wire reels to the wire placer.

Fig. 18 is a sectional view on the line 18—18 of Fig. 17.

2

Fig. 20 is a sectional view on an enlarged scale of a guide 133, the section being on line 20—20 of Fig. 13.

Fig. 21 is a sectional view on line 21—21 of Fig. 20.

Fig. 22 is a view in the direction of arrow 22 of Fig. 20.

Fig. 23 is a like view on enlarged scale of a shoe 146 or 147 shown in Fig. 10.

Fig. 24 is a view in the direction of arrow 24 of Fig. 23.

Fig. 25 is a sectional view on line 25—25 of Fig. 23.

Figs. 26—35 are views on enlarged scale showing steps of making a guide shoe 139. Figs. 26 and 27 are side and end views respectively of one of the two longer rods which are used to make the shoe 139. Figs. 28 and 29 are side and end views respectively of one of two shorter rods which are used to make the shoe 139. Figs. 30 and 31 are plan and end views respectively of a welded assembly of the two larger and the two shorter rods. Figs. 32 and 33 are side and end views of the welded assembly after cutting off certain portions. Figs. 34 and 35 are side and end views respectively of the shoe 139 before attachment to the guide 133.

Referring to Figs. 1 to 3 leg frames 20 and 21 support plates 22 and 23 respectively which support bars 25 and 26 (Fig. 9) that provide a track for a carriage or shuttle which includes bars 27 and 28 carrying pins 29 supporting rollers 30 which engage the bars 27 and 28 which are attached to two spacer blocks 31 and 32 which

support bearing brackets 33 and 34 respectively. Brackets 33 and 34 are attached by pins 35 and 36, respectively, to lugs 37 and 38 respectively of plates 39 and 40, respectively, hingedly connected by pins 41 and 42, respectively, with hinge plates 43 and 44, respectively, which are attached to the ends of the bars 27 and 28. Pin 35 (Fig. 3) passes through ears 33a of bracket 33 and is pinned thereto (Fig. 3). Pin 36 passes through ears 34a of the bracket 34 and is pinned thereto.

Bracket 33 (Figs. 1 and 9) is connected by pin 51 with a bearing cap 53 retained by a nut 55 threadedly engaging a screw eye 57 which receives a pin 59 attached to the bracket 33. By loosening the screw 55 the screw eye 57 can be turned counterclockwise to free the cap 53. Bracket 33 and cap 53 provide a bearing for rotatable armature shaft receiving chuck comprising a tubular shaft 61 which a key 63 and a nut 55 (threaded on shaft 61) attach to the hub 67

of a lever 69. Shaft 61 is slotted at 71 and receives a screw 73 whereby an armature shaft received within the bore 75 of the shaft 61 can be clamped by tightening the screw 73. The armature shaft is marked S1 in Fig. 1 and supports a core C1. The movement of the handle 69 is limited by stops 71 and 79 supported respectively by brackets 81 and 83 attached to plate 39 (Fig. 3). Bracket 33 is notched to receive a bar 85 pivoted on a pin 87 and having a core locating blade 89 to be received by the space between core teeth. Before tightening the screw 73 the core is turned so that it can receive the blade 89 thereby locating the core correctly with respect to the shaft 61. The shaft 61 and the supported armature are located correctly with respect to the wire threader to be described when the lever 69 is in engagement with one of the stops 71, 79.

The construction of the parts supported by brackets 34 (Fig. 2) is similar to those supported by bracket 33 and corresponding parts supported by bracket 34 are designated by reference numbers one higher than the numbers applied to parts supported by bracket 33. For example, Fig. 2 shows bearing cap 54, nut 56, screw eye 58, shaft 62, pin 88, bar 86 with its blade 80, lever hub 68 of lever 70 which swings between stops provided by brackets 82 and 84. Shaft S2 supports core C2 and is fixed to shaft 62. Caps 53 and 54 are removable to permit substitution of tubular shafts 61 and 62 which are adapted to receive and chuck armature shafts of other diameters.

Screws 93 and 94 respectively pass through spacers 31 and 32 respectively and are engaged by nuts 95 and 96 respectively which retain washers 97 and 98 respectively to which are attached the ends of a chain 100 which passes around sprockets 101 and 102 respectively fixed to shafts 103 and 104 respectively which support the hubs of levers 105 and 106 respectively connectible with the shafts by clutches 107 and 108 respectively. Shaft 103, for example, is supported by brackets 103b which screws 103a attach to a plate 103c attached to rails 25 and 26 (Fig. 9). By the use of either of levers 106, 107 the shuttle can be moved along its track. When a lever 105 or 106 is not in use it is disconnected from the shaft which supports it. Lever 105, for example, is retained on shaft 103 by a washer 105a retained by a screw 105b. When winding the core C1 the movement of the shuttle is determined by stops 113 and 115 engageable with a plate 117 attached to shuttle bar 28. When the bar 117 is located at 117' (Fig. 1) the core C1 will be in the position represented by the dot-dash rectangle X (Fig. 2). When the shuttle moves left until the bar 117 engages the stop 113, the core will be located in the position represented by the dot-dash rectangle Y (Fig. 1). For winding the core C2 the movement of the shuttle is limited by the engagement of the plate 117 with stops 114 and 116. When the plate 117 engages the left side of stop 116 the core C2 will be located in the position represented by the rectangle X and when the plate 117 at position 117'' engages the right side of stop 114 the core C2 will be in the position represented by rectangle Y. The stops 113, 114, 115 and 116 are levers which are attached to a shaft 120 supported by brackets 121 and 122 attached to frames 20 and 21 respectively. Washers 123 and 124 pinned to the shaft 120 prevent endwise movement thereof. The shaft 120 is turned by knurled discs 125, 126 attached to the ends of the shaft. In order to locate the plate 117 between

the stops 113, 115 or between the stops 114, 116, the shaft 120 is turned so that the stops will clear the plate and the shuttle is then moved to position the plate 117 between end pair of stops.

Referring to Figs. 10 to 13 the wire placer includes a rectangular plate 130 attached to brackets 131 (Figs. 2 and 14) which are supported by the track rails 25 and 26. Plate 130 has an annular boss 132 (Fig. 13) which is radially notched to receive wire guides 133 each having a washer-receiving recess 134 whereby the guides 133 are attached in pairs to the ring 132 by washers 135 and screws 136. Each guide 133 has an elongated orifice 137 which merges with a restricted orifice 138 in a shoe 139 said orifice flaring out at 140 at the end of the shoe (also Figs. 20 and 21). The shoes 139 are welded to the wire guides. Each shoe is adapted to fit into the space or core slot between armature core teeth. Screws 142a (Fig. 12) and screws 143a (Fig. 11) attach rings 142 and 143, respectively, to plate 130. Rings 142 and 143, respectively, retain rotatable rings 144 and 145 each having a plurality of radially arranged wire retaining shoes 146 and 147 respectively. Each ring 144, 145 is made of the parts which are notched to receive the shanks 148a (Figs. 23 and 24) of shoes 146. When an armature core is at position Y (Fig. 1) its core teeth will be at the left of the shoes 139 as viewed in Fig. 1 or to the right as viewed in Fig. 13 but the core teeth will still receive the shoes 147 which serve to retain the windings in position when not engaged by the shoes 139. When a core is at position X (Fig. 2) the core will be to the right of the shoes 139 as viewed in Fig. 2 and to the left as viewed in Fig. 10, but the core will still receive the shoes 146 which serve to retain the windings in position when not engaged by the shoes 139. During the indexing of the core by turning a lever 69 or 70 when the cores are in positions X or Y the rings 144 or 145 will turn with the core.

Referring to Figs. 17 and 19 the reel support 150 comprises a plurality of horizontal bars 151 and vertical bars 152 welded together and supported by a base 153 which rests on the floor. The bars support wire reels or spools. For example, one of the bars such as 151 (Fig. 18) supports a tube 155 secured by a set screw 156 and supporting two reels R1 and Rr located on the left and right side respectively of the bar 151.

Figs. 17 and 19 show the reels on the left front side or left side (Fig. 18) of the reel support. As shown in the drawings there are 54 reels on each side of the support totaling 108 reels which will supply 108 wires for supplying six wires each for 18 coils to be wound simultaneously on the armature core in case it is provided with 18 slots. The three reels which supply wires for coil #1, for example, are marked R1 and the wires extending therefrom are represented by a single line extending from the right hand R1 upwardly to the wire placer. This single line is marked 3/1 meaning that there are three wires for coil #1 provided by the reels on the front side of the reel support. The reels on the rear side of the support which are behind reels R1 also supply three wires for the coil #1. Similar markings are placed on the other reels and the wires leading therefrom to the wire placer.

The wire placer shown in Figs. 10 to 16 is constructed for winding a 14 slot core.

Fig. 14 shows a step in the winding of core C1 having 14 slots and requiring 4 wires for each of the 14 coils. The winding of a series of cores

starts with full wire spools. The wires from these spools are threaded through the wire guides of the wire placer and are anchored to the armature shaft by means of the device shown in Figs. 5 and 6. This wiring anchoring device has a disc 160 having a central hole 161 received by the armature shaft and having notches 162 respectively receiving the wires from the wire guides 133 and shoes 139. After the wires have been placed in these slots they are twisted together so that they will be anchored by the disc 60. In winding a core C1 (Fig. 14) the core moves first toward the right to position X to place the first pass of wires in its slots. Then the core is rotated counterclockwise and is moved to the left to position Y. The core is rotated clockwise and is moved to the right to position X. Finally the core is rotated counterclockwise and is moved to the left to position Y; and as shown in Fig. 14, the winding ends with lever 69 at the end of its counterclockwise movement. During the winding of core C1 the plate 117 has been moved between the stops 113 and 115. After winding the core C1 as shown in Fig. 14 the shaft 120 is rotated clockwise to free all its stops from the plate 117 and the shuttle is moved into the position shown in Fig. 15, thereby causing the end leads of the coils of core C1 to be passed through the slots of the core C2. The shaft 120 has been rotated counterclockwise to place the stops 114 and 116 in position for engagement by the plate 117 which in Fig. 15 engages the right side of stop 114. The wires having been passed through slots of core C2 they are now anchored. Therefore the wires extending from the end leads extending on core C1 can be severed. After severing these wires the bracket 33 is turned into the position shown in Fig. 16 thereby locating the wound core for removal and replacement by an unwound core. The start leads of the coils on core C2 are tied together by a band 165 then the winding of the core C2 continues until completed and its end leads are caused to be placed in the slots of the unwound core then supported by the bracket 33.

The wires which pass through the two lowest wire guides 133 (Fig. 13) are guided by a pair of reels 170 supported by a bracket 171 supported by one of the horizontal bars 151 of the reel support.

The shoes 139 of the wire guide 133 shown on a larger scale in Figs. 20-22 are each constructed in the following manner. Two rods 200 (Figs. 26, 27) each having flat surfaces 201 and cylindrical surfaces 202 are assembled with two rods 203 (Figs. 28, 29) having flat surfaces 204; and these parts are united by brazing as shown in Figs. 30 and 31. This assembly is machined to the dot-dash lines to make the part shown in Figs. 32 and 33. This completed shoe is shown in Figs. 34 and 35. It has groove surfaces 139a which meet at lines 138. The surfaces defining the restriction 138 and flare 140 are provided by the cylindrical surfaces of the rods 200 and 203 designated respectively by circles 200x and 203x. The shoes 139 are united with the guides 133 by brazing.

The shoes 146 are shaped as shown in Figs. 23-25. Each has a shank 146a and converging surfaces 146b which enter into the space between adjacent core teeth near the periphery of the armature core and the shoe engages the wires placed in the core slot, as the shuttle moves the core through the wire placer. Shoes 147 are made like shoes 146.

After a pass of the core from right to left (Figs. 1-2), which locate the core at position Y, the core and shoes 147 are rotated together and the right coil end portions are ready to be placed against the right end of the core, said portion being between the shoes 147 and the core axis and being between the shoes 147 and the wire guide shoes 139. During a pass of the core through the wire placer from left to right, the core receives the shoes 139 and the coil-end-portions are placed against the right core-end. Before the core leaves the shoes 147 it receives the shoes 146 which are over the coil-active-sides when the pass ends and the core is located at position X (Fig. 2) with the shoes 146 just inside the left end portions of the core slots. Then the core and the shoes 146 are rotated together and the left coil end portions are ready to be placed against the core, said portions being between the shoes 146 and the core axis and between the shoes 146 and the wire guiding shoes 139. During a pass of the core through the wire placer from right to left, the core receives the shoes 139 and the right coil end-portions are placed against the right core-end. Before the core leaves the shoes 146 it receives the shoes 147, which are over the coil-active-side, when the pass ends and the core is located at position Y (Fig. 1). During the winding of a core at least one of the shoes 146, 147 is always in a core slot to pack down the wires of the coil-active-side and to retain the wires during indexing of the core.

While the embodiment of the present invention as herein disclosed, constitutes a preferred form, it is to be understood that other forms might be adopted, all coming within the scope of the claims which follow.

What is claimed is as follows:

1. A machine for winding wires into slots of armature cores assembled with shafts comprising a fixed wire placer having a plurality of shoes arranged in a circular row and each adapted to be received by a core slot and each having a passage receiving wires from supply spools, a shuttle, two bearing brackets supported by the shuttle on opposite sides of the wire placer, two rotatable chucks for receiving armature shafts and respectively journaled in the bearing brackets means for moving the shuttle to pass one core at a time through the row of wire placing shoes, levers respectively for rotating the chucks a predetermined amount between passes of a core through the coil placer, means respectively operating to limit shuttle movement to the ranges of movement respectively required for winding the armature cores supported by the brackets a member which is temporarily a part of the machine and provides for the initial anchoring of the ends of the wires which pass through the shoes of the wire placer said member being supported by the shaft of the first of a series of armatures to be wound, the wire anchoring means for the windings of a succeeding armature being provided initially by the end leads of windings of the preceding armature which are severed, after the partial application of windings of a succeeding armature.

2. A machine according to claim 1 in which each chuck comprises a tubular shaft having a split portion with which a clamp screw cooperates to tighten it around the armature shaft, in which each bearing bracket includes a portion fixed to the shuttle and a cap portion attached to the fixed portion and movable relative thereto to

permit replacement of the chuck by another adapted to receive an armature shaft of a different diameter and means for securing the cap in chuck retaining position.

3. A machine according to claim 1 in which each bracket is hingedly connected with the shuttle so that, while one bracket supports an armature in position for winding, the other bracket can be located for facile removal of a wound armature.

4. A machine according to claim 1 in which the means which limits shuttle movement to either of two winding ranges comprises a member movable with the shuttle, four spaced stop bars between two of which said member can move when one core is being wound and between the other two of which said member can move when the other core is being wound, and a shaft which supports the bars and which is turned to retract the bars from the path of movement of said member to permit movement of said member from the range between one set of bars into the range between the other set of bars.

5. A machine for winding wires into slots of armature cores comprising a fixed wire placer having a plurality of shoes arranged in a circular row and each adapted to be received by a core

slot and each having a passage receiving wires from supply spools, a shuttle, a chuck rotatably supported by the shuttle for receiving and gripping the armature shaft which supports the core, means for rotating the chuck, means for moving the shuttle to pass the core through the row of wire placing shoes, two rings located on opposite sides of said shoes and concentric therewith and rotatably supported by the placer, wire retaining shoes supported by each ring in a circular row concentric with the wire placing shoes and each adapted to be received by a core slot, and means for so limiting movement of the shuttle in either direction that, at the end of a shuttle movement, a row of wire retaining shoes remains in the end portions of core slots, said shoes rotating with the core when turned preparatory to the next movement of the shuttle.

EDWARD W. COLLINS.
